(57) CLAIM

The ornamental design for a shoe insole, as shown and described.

DESCRIPTION

FIG. 1 is a front perspective view of a shoe insole showing my new design;

FIG. 2 is a top view thereof; and,

FIG. 3 is a rear perspective view thereof.

The broken lines immediately adjacent to the photographic areas define the bounds of the claimed design and form no part thereof. The broken lines depicting the remainder of the shoe insole form no part of the claimed design.
